UNITED STATES PATENT OFFICE

MILLARD B. LUCKER, OF BENTON HARBOR, MICHIGAN, ASSIGNOR, BY MESNE ASSIGNMENTS, TO THE DAYTON MALLEABLE IRON COMPANY, OF DAYTON, OHIO, A CORPORATION OF OHIO

LIFTING JACK

Application filed July 29, 1929. Serial No. 381,904.

My invention relates in general to pushing apparatus and has more particular reference to a jack for automobiles.

An important object of my invention is to provide an improved automobile jack of the double lift type, that is to say, a jack having a frame and a multi-part lifting member arranged in telescopic relationship, the principal feature of the jack being its low initial or collapsed dimension and its relatively large extended dimension.

Another important object of my invention is to provide a simple and positive means for yieldably preventing an extensible jack member from rotating within the jack housing during the projection of the member.

Another important object of my present invention is to provide, in a double lift jack, simple and positive means for yieldably preventing an extensible jack member from rotating in its housing while being projected therefrom, which means will permit of rotation of the extensible member at the limits of its travel.

A further object of my present invention is to provide a friction device carried by an extensible jack member and having interlocked engagement with a grooved portion of the jack frame whereby the rotative urge imparted to the extensible member by the operating means may be counteracted during the extension of the member from its frame.

Still another object of my invention is to provide in a pushing apparatus, a friction clutch of simple rugged and inexpensive construction and positive action for preventing the relative rotation of the extensible pushing member within its supporting frame.

Numerous other objects and advantages of the invention will be apparent as it is more fully understood from the following description and taken in connection with the accompanying drawing discloses a preferred embodiment thereof.

Referring to the drawing:

Figure 1 is a vertical cross section taken longitudinally through an automobile jack embodying my present invention;

Figure 2 is a perspective view of the several

parts of the friction clutch or brake for the extensible member of the jack;

Figure 3 is a sectional view of the jack illustrated in Figure 1, showing the application of a modified friction clutch to the extensible member; and

Figure 4 is a perspective view of the several parts of said modified friction clutch.

To illustrate my present invention I have shown on the drawing an automobile jack including a support frame comprising an extended base 11 and a cylindrical sleeve 13 extending upwardly of the base and providing a housing. A bearing support 15 is arranged at the upper end of the cylindrical sleeve and comprises a band extending across the open top of the cylindrical sleeve and vertically spaced thereover. A bearing 17 is formed in the bearing support 15 in vertical alignment above the upper end of the sleeve 13. Strengthening webs 19 are arranged in the junction of the sleeve 13 with the base 11 and with the bearing support 15.

The sleeve 13 provides a cylindrical channel 37, which extends through the base 11 to the upper end of the sleeve, which is formed to provide a bearing seat 39. The lower end of the bearing 17 and the bearing seat 39 are spaced sufficiently to permit a beveled gear 21 to be slid edgewise therebetween, in order that it may be pushed in the bearing 17, the hub 23 thereof sliding upwardly into the bearing 17 after the gear has been inserted edgewise as aforesaid. The beveled gear is supported in position by means of a roller bearing 41, which may be inserted edgewise between the seat 39 and the lower end of the gear 21, after the latter has been pushed in the bearing 17. The roller bearing 41 is provided with a central aperture of equal diameter to the channel 37. The beveled gear 21 is thus rotatably mounted in the bearing 17 and has a toothed periphery 25 extending outwardly to engage a cooperating driving pinion 27 carried at the end of a stub shaft 29, which is suitably journaled in a bearing 31 formed in one side of the bearing support 15. The shaft 29 is provided with a non-circular central socket 35, which is adapted to accommodate the non-circular end of a suit-

able jack operating handle (not shown) by means of which the pinion and gear 21 may be rotated in their respective bearings from a distance.

3 The extensible or lifting members comprise an inner shaft 45 having threads 47 extending throughout its length, and an outer sleeve 49 provided with external screw threads 51 extending from the upper end of the sleeve to a point spaced from the lower end thereof.

10 The threads 51 are adapted to co-operate with internal screw threads 57 formed in the bore of the beveled gear 21, which thus provides a rotatable threaded collar mounted in the frame, rotation of which will cause the threaded sleeve 49 to move axially in the frame, providing the sleeve is held against relative rotation, therein. The sleeve 49 also has an internally threaded portion 53 at its 15 upper end, the threads of which are adapted to co-operatively engage the threads 47 of the inner extensible member 45 so that, upon rotation of the outer extensible member, the inner member will be projected therefrom provided it is held against rotation.

25 A stop or peg 59 is set in the groove of the threads 47 at the lower end of the inner extensible member in order to limit the projection of the inner member by engaging the lower end of the threaded portion 53 when the inner member is in fully extended position with respect to the sleeve. A similar stop 83 is set in the threads 51 of the sleeve 49 and performs a similar function by engaging the lower end of the gear 21. In addition, the peg 83 provides for driving engagement between the gear 21 of the sleeve whereby the sleeve may be locked for rotation with the gear 21.

40 In assembling the device, the inner member is telescoped into the sleeve through the lower end, and the threads 47 thereof are meshed with the threads 53 of the sleeve. After the shaft 45 is thus assembled, the sleeve and shaft are together inserted into the sleeve 13 through the lower end thereof by sliding the parts longitudinally through the channel 37 and through the opening 43 of the lower bearing. The external threads 51 of the 45 sleeve are mated with the inner threads 57 of the rotatable collar or gear 21. A peg 61 is then set in the groove of the threads 51 of the sleeve above the collar 21, which peg by engaging the upper surface of the gear, limits the downward movement of the extensible sleeve. This peg also provides for driving engagement between the gear and sleeve when the latter is at the lower limit of its travel. A load carrying head 63 is finally mounted to the upper end of the inner extensible member 45.

Upon rotation of the gear 21, the extensible members 45 and 49 being in the collapsed position, illustrated in Figure 1, the outer or tubular extensible member 49 will be pro-

jected axially by the cooperation of the threaded portion 57 of the gear and the threads of the sleeve, providing of course that the sleeve is prevented from rotating within the frame.

I provide novel and improved means comprising a friction clutch for preventing such rotation during the extension of the sleeve, said means being yieldable to permit rotation of the sleeve with the gear 21 when at the upper and lower limits of its travel. The friction clutch is mounted to the lower unthreaded end 69 of the sleeve 49 and comprises a pair of collars 65 having central openings 67 of sufficient size to permit the collars to 50 loosely fit upon the lower end 69 of the sleeve. The lower end of the sleeve is formed to provide a shoulder 79 against which the uppermost collar 65 may seat. The collars are provided with out-standing ears 75, which are adapted to engage in slots 77 formed longitudinally along the inner surfaces of the sleeve 13. Resilient means are provided between the collars 65 for normally urging the same apart upon the lower end 69 of the 55 sleeve, the lowermost edge of the portion 69 being peened over, as at 71, to retain the lowermost collar upon the portion 69.

I prefer to form the resilient means as a plurality of springs 81, comprising washers of spring steel having central openings of sufficient size to permit the washers to embrace the restricted portion 69 of the sleeve. The washers are bent or off-set, as at 85, and are secured together in opposed relationship in any convenient manner, such as by spot welding, riveting or the like, to form a unitary resilient member, which may be compressed between the collars 65 when the same are assembled to the lower end of the sleeve.

As a modification I merely form the resilient spring 81 as a single distorted washer of spring steel as shown in Figures 3 and 4 of the drawing. The action of the springs 81 is to force the collars 65 apart and to cause a frictional engagement between the collars and the sleeve at the shoulder 79 and the peened over portion 71 sufficient to normally prevent rotation of the sleeve with respect to the collars 65, since the ears 75 of the washers set in the longitudinal groove 77 throughout the movement of the sleeve, relative rotation of the sleeve with respect to the housing 13 is normally prevented. The friction connection between the sleeve and the collars 65, however, is not sufficient to prevent the rotation of the sleeve when it reaches the limits of its travel, and the pegs 61 and 83 engage the gear 21 to form a positive drive connection therebetween.

Operation

When the gear 21 is rotated in its bearing, the sleeve 49, being held against rotation through the friction device, will be raised ax-

ially by the co-operation of the threads 57 and 51, and will carry with it the inner extensible member 45. When the sleeve is projected sufficiently, the peg 83 will engage the lower surface of the gear 21 and form a driving connection whereby further rotation of the gear 21, will rotate the sleeve. When this occurs, the inner member 45 being held against rotation by the load supported thereon will be extended axially through the sleeve until the peg 59 at its lower end engages the lower end of the internally threaded portion 53 of the sleeve at which point the device is in its fully extended position. By reversing the rotation of the gear 21, the sleeve will be withdrawn into the housing 13 until the peg 61 at the upper end thereof engages the gear 21 and forms a driving connection whereby the sleeve may again be rotated by the gear, such rotation resulting in the retraction of the inner member 45. The inner member will be retracted until the load carrying head 63 engages the upper end of the sleeve 49 in which position the jack is in fully retracted condition.

The friction device whereby the sleeve is prevented from rotating in the housing 13 during its projection and retraction, but permitted to rotate at the limits of its travel, provides a maximum friction in a construction embodying extreme simplicity and durability. Construction also lends itself readily to production on an economical basis, it being apparent that the collars 65 and springs 81 may be stamped from sheet metal stock. No accurate machining of the parts is necessary, no auxiliary housings are necessary and the construction is such that it may readily be embodied in a commercial article.

It is thought that the invention and numerous of its attendant advantages will be apparent from the foregoing description, and it will be apparent that various changes may be made in the form, construction and arrangement of the parts without departing from the spirit and scope of the invention or sacrificing any of its material advantages, the form herein described being my preferred embodiment.

Having thus described my invention what I claim as new and desire to secure by Letters Patent is:

1. In an extension device, a grooved frame, an extensible lifting member arranged in said frame, an operating member rotatably mounted in said frame and having threaded connection with said extensible member whereby the extensible member may be moved axially with respect to said frame upon rotation of the operating member, and a friction device carried by said extensible member and engaging said frame whereby to prevent relative rotation of the extensible member with respect to the frame, said friction device comprising a collar mounted on the inner end of

said extensible member and spring means urging said collar to frictionally engage the extensible member to prevent relative movement between the collar and extensible member, said collar having a projecting ear adapted to engage the grooved portion of said frame.

2. In an extension device, a frame, an extensible lifting member arranged in said frame, an operating member rotatably mounted in the frame and having threaded connection with said extensible member whereby to move the same axially, a collar carried on the lower end of said extensible member and resilient means for urging said collar to frictionally engage the extensible member whereby to normally prevent relative rotation therebetween and co-operating means formed and arranged in the collar and the frame for preventing said collar from rotating with respect to the frame.

3. In an extension device, a frame, an extensible lifting member arranged in the frame in position to be retracted and projected axially therefrom, an operating member rotatably mounted in the frame and having operative connection with said extensible member for imparting axial movements thereto, said extensible member having a shoulder and an unthreaded projection at its lower end, a collar mounted on said projection and engaging said shoulder, a second collar mounted on said projection, said projection being peened over at its lower edge to retain the collars thereon, and spring means normally urging said collars apart on said projection whereby to frictionally engage the extensible member, said collars being provided with outstanding ears and said frame being provided with a longitudinal groove in which said ears are engaged.

4. In an extension device, a frame, an extensible member arranged in said frame for projection and retraction therefrom, an operating member arranged in said frame and having cooperative engagement with said extensible member to move the same in the frame and means comprising a collar and a spring normally urging said collar to frictionally engage the extensible member, said collar having keyed connection with the frame whereby to normally prevent relative rotation of the collar with respect to the frame while permitting the same to move longitudinally.

5. In an extension device, a frame, an extensible member arranged in said frame for projection and retraction therefrom, an operating member arranged in said frame and having cooperative engagement with said extensible member to move the same in the frame and means comprising a collar and a spring normally urging said collar to frictionally engage the extensible member, and means for keying said collar to a formed portion of said frame whereby to prevent relative rotation of the collar with respect to the frame.

while permitting longitudinal movement of the collar.

6. In an automobile jack, a frame providing a housing having an upright channel, an extensible member arranged in said channel for projection and retraction therefrom, a sliding member carried in said frame at the upper end of said channel and having co-operative engagement with said extensible member to move the same in the channel and means comprising a collar having frictional engagement with the extensible member, a spring urging said collar frictionally against said extensible member, and means for keying said collar for splined engagement with the frame whereby to normally prevent relative rotation of the extensible member with respect to the frame.

7. In an automobile jack, a frame providing a housing having an upright channel, an extensible member arranged in said channel for projection and retraction therefrom, a sliding member carried in said frame at the upper end of said channel and having co-operative engagement with said extensible member to move the same in the channel and means comprising a collar having frictional engagement with the extensible member, a spring urging said collar frictionally against said extensible member, and means for keying said collar for splined engagement with the frame whereby to normally prevent relative rotation of the extensible member with respect to the frame, and a second extensible member having co-operating engagement with the first mentioned extensible member.

In witness whereof I have hereunto subscribed my name.

MILLARD B. LUCKER.
